UNITED STATES PATENT OFFICE.

ROBERT F. MITCHELL, OF NEW HAVEN, CONNECTICUT.

WATCH-WINDING MECHANISM.

SPECIFICATION forming part of Letters Patent No. 292,838, dated February 5, 1884.

Application filed October 22, 1883. (No model.)

To all whom it may concern:

Be it known that I, ROBERT F. MITCHELL, a citizen of the United States of America, residing at New Haven, in the county of New Haven and State of Connecticut, have invented certain new and useful Improvements in Watch-Winding Devices, of which the following is a specification, reference being had therein to the accompanying drawings.

10 This invention relates to that class of watch-winding devices known as "stem-winding." Stem-winding devices for watches, as constructed prior to my invention, were operated by a rotary movement of a part or the whole 15 of the case-stem, or a radial shaft passing through the stem, either of which operated upon a train of gear in the watch to wind up the mainspring.

The object of this invention is, first, to provide a winding device which shall be simple and cheap in construction; second, to furnish a device for winding the mainspring which shall occupy a very small space in the watch, affording more room for the time-train of the 25 watch; third, to provide a stem-winding device which shall not reduce the strength of the case-stem by having any of the working parts located in or passing through said case-stem.

It consists of a stem-winding device in which 30 the several parts which constitute the device are arranged in such a novel manner that by oscillating the case-stem to and fro, while holding the watch in a stationary position, the mainspring is wound up.

35 To enable others to make and use my improved winding device, I will give a clear and concise detailed description of the same.

Letters of like name and kind refer to like parts in each of the figures.

40 Figure 1 is a view of a watch having a portion of the rear case removed, exposing to view the position of the parts of the winding device, also the mode of operating the same. Fig. 2 shows a cross-section of the case-ring C, in Fig. 4, on line x x; also showing an edge view 45 of the winding-train of gear and their relative position with the driving-ratchet E. Figs. 3 and 4 are detailed views, fully described hereinafter.

50 A represents the rear case of a watch, hav-

ing a portion removed to show internal parts which constitute the winding device.

B is the front portion of the case, and is provided with a flange, a. The case-ring C is provided with the case-stem D, also an inner 55 projection, b, to which is hinged the pawl c. The small spring d is secured to the inner side of the case-ring C, and presses upon the pawl c, holding said pawl c closely upon the ratchet E. The lower portion of the ratchet 60 E is removed in the drawings to show the manner in which the gear e (which is secured to the under side of the ratchet E and both revolving upon the same journal or screw i) meshes into the toothed periphery of the pinion upon the mainspring barrel or post g. h is an inner plate of the watch, upon which are arranged the winding and time trains of the 65 watch. The flange a upon the case B, Fig. 3, is provided with an opening, k, in which the 70 inner projection, b, on case-ring C operates as the case-stem D is oscillated to and fro. The ends of this opening k in the flange a serve as a stop to regulate the throw or movement of the case-stem D. I am aware that 75 other means may be used to serve as a stop, but I prefer the mode described because of its cheapness and efficiency. The case-ring C is made in width to correspond with the flange a of the case B, said ring C being adapted, 80 when placed in the position shown in Fig. 1, to move upon the flange a about the center of the case or watch.

The several parts being constructed and arranged as shown and described, the operation 85 of the winding device is as follows, viz: By taking the watch in one hand and with the other hand bringing the case-stem D back into the position indicated by the dotted lines in Fig. 1, the pawl c is drawn over the teeth of 90 the ratchet E, and the inner projection, b, on the case-ring C striking against the flange a at the extremity of the opening k, prevents the pawl c being carried beyond the ratchet E. Having thus drawn the case-stem D into 95 the position of the dotted lines in Fig. 1, by carrying the case-stem forward again, the pawl c being interlocked in the tooth of the ratchet E, will cause the ratchet and its appurtenant gear e to revolve upon the journal or screw i, 100

which in turn rotates the mainspring barrel or post *g*. The moving of the case-stem *D* is continued in this manner until the mainspring is wound up.

5 I have shown the pawl *c* as operating upon a ratchet-wheel and operating an intermediate gear, because the mainspring can be wound up with a less number of oscillations of the case-stem by such arrangement; but the spring can 10 be wound up if the pawl *c* be made to operate directly upon the pinion on the mainspring barrel or post *g*.

Having described my invention, what I claim as new, and desire to secure by Letters Patent, 15 is—

1. A stem-winding device for watches, consisting of the case-stem *D* and case-ring *C*, being adapted to move upon the case in an arc concentric with the watch-case, said case-ring 20 *C* being provided with a projection, *b*, to which

are attached the pawl *c* and spring *d*, which operate upon the ratchet *E*, gear *e*, and mainspring barrel or post *g*, the case *B* being provided with the opening *k* in the flange *a*, substantially as described and shown, all being 25 arranged to operate as and for the purpose set forth.

2. In a stem-winding device for watches, the combination of the case-stem *D* and movable case-ring *C*, pawl *c*, spring *d*, ratchet *E*, gear 30 *e*, plate *h*, mainspring barrel or post *g*, and journal *i*, all arranged to operate substantially as and for the purpose set forth.

In testimony whereof I affix my signature in presence of two witnesses.

ROBERT F. MITCHELL.
